United States Patent

Des. 240,685
Patented July 27, 1976

240,685

CURIO CABINET

Leonard Eisen, 14 Lomas Lane,
Montvale, N.J. 07645

Filed July 30, 1974, Ser. No. 493,156

Term of patent 14 years

Int. Cl. D6—04

U.S. Cl. D6—148

FIG. 1

FIG. 2

FIG. 3

FIG. 1 is a front perspective view of the curio cabinet showing my design;

FIG. 2 is a side view thereof; and

FIG. 3 is a top view thereof.

The back of the curio cabinet is conventionally flat.

I claim:

The ornamental design for a curio cabinet, as shown and described.
